UNITED STATES PATENT OFFICE.

KARL JOHAN SVENSSON, OF LIDINGO VILLASTAD, AND KARL AXEL PATERIK NORLING,
OF SODERTORNS VILLASTAD, SWEDEN.

CENTRIFUGAL TREATMENT OF LIQUIDS.

Application filed December 14, 1926, Serial No. 154,680, and in Sweden January 11, 1926.

When purifying or separating liquids by centrifugal treatment it is often necessary, in order to obtain a high separating efficiency of the centrifugal drum, to heat said liquids to a predetermined temperature before they are introduced into the centrifugal drum, and this is especially the case with thick oils as the temperature has a great effect on their viscosity. A very common method to employ when separating such liquids is to pass them through an electric heater before feeding them into the drum. For oils containing solid impurities, such as slime, sludge and the like, it is also advantageous to mix them with a greater or smaller quantity of water or of some other suitable liquid which is heavier than the oil and which, during its separation in the drum, extracts the solid impurities suspended in the oil, thus facilitating separation. Usually this additional liquid or so-called "wash" is mixed with the oil in a tank, from which the mixture is pumped or conducted in some other way into the centrifugal drum where the "wash" is separated together with other fluid or solid heavy impurities.

One disadvantage of using electric heaters, however, is that if the supply of liquid should stop, for instance when the feed tank is emptied, and the electric current be not switched off immediately the quick temperature rise causes the heater elements to burn out. In order to prevent this, automatic thermo-switches are sometimes used but, as a rule, these are very expensive.

The present invention has for its object a simple and cheap arrangement by which the risk of burning out electric heaters is completely eliminated, a homogeneous mixture of the liquids to be separated and "wash" is obtained always, together with a thorough washing of them, and only a relatively small amount of washing liquid is used, thus saving "wash" and at the same time reducing the electric power consumption in the heater.

According to the present invention the improved arrangement comprises a centrifugal separator, a feed pump therefor, one or more electric heaters situated in the feed pipe line of the separator, either or all of them on the suction side, or all on the discharge side, of the pump, or one or more on both sides of the pump, one or more receptacles for additional liquid or "wash" and

the necessary feed piping with valves or cocks, wherein the suction pipe line from the "wash" receptacle or receptacles to the feed pump is connected with the suction pipe line for the liquid to be purified or separated in such a way that the feed pump can suck suitable proportions from the two pipe lines simultaneously, or "wash" only, if the supply from the other pipe line should stop, and wherein the two liquids or liquid mixtures pass through the heater or heaters in a mixed state or are introduced separately into the heater or heaters and mixed before they are led into the centrifugal apparatus in order to be separated or purified.

Figures 1 and 2 of the accompanying drawings show in diagrammatic side elevation two different arrangements according to the present invention.

In both figures: *a* is a tank or container for the liquid to be purified, *b* a smaller container for "washing" liquid, *c* a centrifugal separator of known type having a feed vessel *d*, a discharge pipe *e* for the purified liquid and a discharge pipe *f* for separated impurities and "wash", whilst *g* is an electric heater having a feed pipe *h* leading to the feed vessel *d* of the separator *c*. The tank *b* is arranged as a settling tank and has a vertical baffle *j* extending almost to its bottom, an outlet *k* situated some distance above said bottom, and an inlet *m* at its top into which the liquid discharged from the pipe *f* is introduced. In this tank *b* most of the separated impurities discharged with the wash will settle down and only the purest part of the liquid therein will be discharged through the outlet *k*. *n* is a drain cock in the bottom of the tank *b* for removal of the settled impurities.

In the arrangement shown in Figure 1 a feed pump *o* has a discharge pipe *p* leading to the heater *g*, whilst a pipe *q* leads from the tank *a* to the pump *o* and is provided with a control valve or cock *r* said pipe *q* being arranged so that a part thereof is on a higher level than the inlet of the pump *o*. The outlet *k* of the tank *b* is connected with the pump *o* by a pipe *s* furnished with a valve or cock *t*, the tank *b* being so arranged that the normal level *u* of the liquid therein is higher than the inlet to the pump *o*.

The working of the plant when purifying

oil, for instance, with water as the washing liquid is as follows:—

The centrifugal separator *c* and the pump *o* having been started, the cock *t* is opened and the electric current for the heater *g* is switched on; water is thus pumped through the heater *g*, heated, and delivered through the pipe *h* to the feed vessel *4* and thence to the drum of the separator *c*, heats its

- 10 parts and forms the necessary water seal in the drum before the oil can be fed in. The valve *r* for the oil is then opened and the two valves *r* and *t* are adjusted so that suitable proportions of the two liquids are
- 15 drawn in and pumped up through the heater *g* into said drum, wherein the water and other impurities are separated from the oil and discharged through the pipe *f* to the tank *b* in order to be cleaned to a certain
- 20 extent, and then returned by the pipe *s* to the pump *o*. The purified oil is discharged through the pipe *e* and collected in a suitable receptacle, only the inlet *v* of which is shown, or if it is necessary to purify the
- 25 oil more than once it is discharged into the tank *a*.

If, for any reason the oil feed through the pipe *g* should cease, the pump *o* would continue to pump washing water through the heater *g* as the pipe *g* and liquid level *u* in the tank *b* are arranged relatively to the pump *o* as described above, thus there is no risk of burning out the heater *g*.

In the arrangement shown in Figure 2, *w* is a pump for the liquid to be separated, *x* a suction pipe leading from the tank *a* to the pump *w* and provided with a control valve or cock *y*, *z* a pump for washing liquid only, and connected with the tank *b* by a suction pipe *s'*, provided with a valve *t'*.

The discharge outlets of the pumps *w* and *z* are connected with a common discharge pipe *p'* leading to the heater *g*.

The action of the arrangement shown in Figures 1 and 2 is much the same although the position of the pump *w* relatively to the pipe *x* and to the level *u* of the liquid in tank *b* is of no importance as the suction sides of the two pumps are quite independent of one another.

Although the arrangement shown in Figure 2 is a little more expensive than that shown in Figure 1, it presents advantages when treating liquids which emulsify easily by the violent agitation which takes place

inside a pump. This risk is obviated entirely in the arrangement shown in Figure 2 as the liquids are not mixed until they have passed through the pumps *w* and *z*.

Both arrangements can be used also in cases where a washing is not desired or necessary, by leaving the valves *t* and *t'* shut, though there is then a risk of burning the heater *g*.

Although only two arrangements of the present invention are shown, considerable variations can be made within the scope of the invention. For instance, the heater *g* can be situated on the suction side instead of on the discharge side of the pump or pumps, the different liquids can be introduced separately into the heater and mixed there and so on.

We claim:—

1. An arrangement for the centrifugal separation of liquids containing solid particles in suspension, comprising centrifugal separating apparatus, pumping means for supplying thereto said liquids to be separated, and electric heating apparatus for heating said liquids before delivery to the separator, said pumping means being provided with two lines of suction piping for the simultaneous supply to the electric heating apparatus of the liquid to be separated and a wash liquid, the arrangement being such that should the supply of liquid to be separated be interrupted, the wash liquid will continue to be supplied, to protect said heating apparatus.

2. An arrangement for the centrifugal separation of liquids containing solid particles in suspension, comprising centrifugal separating apparatus, pumping means for supplying thereto said liquids to be separated, electric heating apparatus for heating said liquids before delivery to the separator, delivery piping from the pumping means to said heating apparatus, said pumping means being provided with two lines of suction piping for the simultaneous delivery to the electric heating apparatus of the liquid to be separated and a wash liquid, the arrangement being such that should the supply of liquid to be separated be interrupted, the wash liquid will continue to be supplied, to protect said heating apparatus.
